(57) **CLAIM**

The ornamental design for a frog bag, as shown and described.

DESCRIPTION

FIG. 1 is front view of the frog bag according to the design showing the legs in an unsupported position to better illustrate the zipper placement on the rear legs;

FIG. 2 is a rear view thereof showing the legs in an unsupported position to better illustrate the zipper placement on the front legs;

FIG. 3 is a right side view thereof showing the legs in an unsupported position to better illustrate the zipper placement on the left arm and leg;

FIG. 4 is a left side perspective view thereof with the legs straightened to better illustrate the leg geometry;

FIG. 5 is a top view thereof with the legs straightened to better illustrate the leg geometry; and,

FIG. 6 is a bottom view thereof with the legs straightened to better illustrate the leg geometry and zipper placement.

The dash-dash lines on the surface of the frog bag represent stitching and form a part of the claimed design. The grey patterned surfaces in the drawings describe a contrasting appearance. The black shaded elements in the drawings represent a further contrasting appearance between the grey patterned surfaces and the non-patterned surfaces of the drawings.
